COMBINED BICYCLE PEDAL AND REFLECTOR

Harry Golden, New York, N.Y., assignor to Ideas For Auto and Bike Specialties, Inc., New York, N.Y., a corporation of New York

Filed Aug. 11, 1969, Ser. No. 18,636

Term of patent 14 years

Int. Cl. D12—14

U.S. Cl. D90—14

FIG. 1

FIG. 2

FIG. 3

FIG. 4

FIG. 5

FIG. 1 is a top plan view of a combined bicycle pedal and reflector embodying my new design, with the bottom plan view being identical in appearance;

FIG. 2 is an end view taken from the right hand end of FIG. 1 and showing the reflector portion thereof;

FIG. 3 is a front elevational view thereof, with the rear elevational view being identical in appearance;

FIG. 4 is an end view thereof, taken from the left hand end of FIG. 1; and

FIG. 5 is an exploded perspective view thereof with the reflector being shown disassembled from the pedal for illustrative purposes.

I claim:

The ornamental design for a combined bicycle pedal and reflector, as shown and described.
